(57) **CLAIM**

The ornamental design for an extruded frame member for EMI enclosure, as shown and described.

DESCRIPTION

FIG. 1 is a perspective fragmentary view, as seen from the front right, of our design for an extruded frame member for EMI enclosure.

FIG. 2 is a perspective fragmentary view, as seen from the front left, of our design shown in FIG. 1.

FIG. 3 is a front view of our design shown in FIG. 1, rotated 180 degrees about the longitudinal axis.

FIG. 4 is a fragmentary top plan view of our design shown in FIG. 1.

FIG. 5 is a fragmentary left side view of our design shown in FIG. 1.

FIG. 6 is a front view of our design shown in FIG. 1.

FIG. 7 is a fragmentary right side view of our design shown in FIG. 1; and,

FIG. 8 is a fragmentary bottom plan view of our design shown in FIG. 1.
